(57) **CLAIM**

We claim the ornamental design for a brick, as shown and described.

DESCRIPTION

FIG. 1 is a front-left perspective view of a brick of the new design;

FIG. 2 is a front elevational view of the brick of FIG. 1;

FIG. 3 is a rear elevational view of the brick of FIG. 1;

FIG. 4 is a top plan view of the brick of FIG. 1;

FIG. 5 is a bottom plan view of the brick of FIG. 1;

FIG. 6 is a left side elevational view of the brick of FIG. 1, the right side elevational view being a mirror image thereof; FIG. 7 is a front-left perspective view of a brick of the new design;

FIG. 8 is a front elevational view of the brick of FIG. 7;

FIG. 9 is a rear elevational view of the brick of FIG. 7;

FIG. 10 is a top plan view of the brick of FIG. 7;

FIG. 11 is a bottom plan view of the brick of FIG. 7; and, FIG. 12 is a left side elevational view of the brick of FIG. 7, the right side elevational view being a mirror image thereof.

The broken lines depict portions of the brick that form no part of the claimed design.
